UNITED STATES PATENT OFFICE

140,494

DESIGN FOR AN OFFSET VALVE VULCANIZING BLOCK

Hyman S. Aaronson, Meriden, Conn., and Lyle L.
Austin, Mount Vernon, N. Y.

Application September 24, 1943, Serial No. 111,200

Term of patent 14 years

(Cl. D55—1)

To all whom it may concern:

Be it known that we, Hyman S. Aaronson and Lyle L. Austin, both citizens of the United States of America, residing in Meriden, county of New Haven, State of Connecticut, and Mount Vernon, county of Westchester, State of New York, respectively, have invented a new, original, and ornamental Design for an Offset Valve Vulcanizing Block, of which the following is a specification, reference being had to the accompanying drawing, forming part thereof.

Fig. 1 is a front perspective view of an offset valve vulcanizing block showing our new design.

Fig. 2 is a bottom perspective view thereof.

We claim:

The ornamental design for an offset valve vulcanizing block, substantially as shown.

HYMAN S. AARONSON.
LYLE L. AUSTIN.
